UNITED STATES PATENT OFFICE.

JOHN R. MILLER, OF READING, PENNSYLVANIA.

HAT.

SPECIFICATION forming part of Letters Patent No. 358,215, dated February 22, 1887.

Application filed January 10, 1887. Serial No. 223,892. (No model.)

To all whom it may concern:

Be it known that I, JOHN R. MILLER, a citizen of the United States, residing in Reading, Berks county, Pennsylvania, have invented 5 certain Improvements in Securing Bands to Hats, of which the following is a specification.

The object of my invention is to so secure the upper edge of a hat-band to the side body of the hat that the external appearance of said 10 band will not be affected, and the fitting of the sweat-band snugly to the inside of the body will not be interfered with. This object I attain in the manner hereinafter set forth, reference being had to the accompanying drawings, in which—

Figure 1 is a view of a hat having a band secured thereto in accordance with my invention; Fig. 2, a sectional plan, on an enlarged scale, of part of said hat, illustrating more 20 fully my improved method of fastening the upper edge of the band; Figs. 3 and 4, views showing methods of fastening which have heretofore been adopted, and Fig. 5 a view illustrating a modification of my invention.

In packing certain classes of hats for the market it is a common practice to stack them up one above another, each hat being driven 25 as far as possible down over the one beneath; hence it is necessary to secure the upper edge 30 of the band *a* to the side body, *b*, of such a hat, in order to prevent the pressing down and folding or wrinkling of the band, which would otherwise result when one hat was pressed down over another.

Heretofore, so far as I am aware, but two 35 methods of securing the upper edge of the band have been adopted, the first being to secure said edge by means of tacking-stitches *d*, Fig. 3, and the second being by means of a 40 row of straight-ahead stitches, *f*, near the upper edge of the band. (See Fig. 4.) The first of these plans is objectionable, because such stitches must be formed by hand, and because, further, the stitches are so wide apart that the 45 thread extending in a straight line from stitch to stitch on the inside of the hat interferes with the laying of the sweat-band snugly against the inside of the hat-body. The second plan, although overcoming these objections, is itself open to the objection that the

row of straight-ahead stitches imparts an unsightly appearance to the band, and hence detracts materially from the salability of the hat.

In carrying out my invention I secure the 55 upper portion of the band to the side body of the hat by a series of fastenings, each of which is independent of the others. As shown in Fig. 2, each of these fastenings consists of a loop passing through the band and body of 60 the hat, the ends of the thread forming the loop being knotted on the inside of the hat. Fastenings of this character can be readily made by means of a sewing-machine so constructed as to form the desired knot, and provided with means for cutting the thread between successive stitches, or the machine may be constructed on the principle of the knot-tyer of a grain-binding machine. Such machine, however, forms no part of my present 70 invention, nor is my invention limited to the securing of the band to the body of the hat by means of a looped and knotted thread. For instance, metallic staples clinched on the inside of the hat, as shown in Fig. 5, may be 75 substituted for each looped and knotted thread, if desired.

If desired, the lower edge of the band may be secured to the body of the hat in the same manner as the upper edge; but this is not essential, as said lower edge may be left free in most cases.

I claim as my invention—

1. A hat the upper edge of the band of which is secured to the body of the hat by a 85 series of fastenings, each independent of the others, all substantially as specified.

2. A hat the upper edge of the band of which is secured to the body of the hat by a series of fastenings, each consisting of a loop 90 knotted on the inside of the hat, all substantially as specified.

In testimony whereof I have signed my name to this specification in the presence of two subscribing witnesses.

JOHN R. MILLER.
